UNITED STATES PATENT OFFICE.

FREDERICK E. GROSVOLD, OF EAU CLAIRE, WISCONSIN, ASSIGNOR OF ONE-HALF TO
DAVID W. JOHNSON, OF MILWAUKEE, WISCONSIN.

SEWER-PIPE CLEANER.

1,151,357

Specification of Letters Patent. Patented Aug. 24, 1915.

Application filed March 26, 1914. Serial No. 827,228.

To all whom it may concern:

Be it known that I, FREDERICK E. GROSVOLD, a citizen of the United States, and resident of Eau Claire, in the county of 5 Eau Claire and State of Wisconsin, have invented new and useful Improvements in Sewer-Pipe Cleaners, of which the following is a description, reference being had to the accompanying drawings, which are a 10 part of this specification.

This invention relates to improvements in sewer pipe cleaners.

It is one of the objects of the present invention to provide a sewer pipe cleaner 15 which is adapted to be easily forced through a sewer pipe which has become plugged or stopped up.

A further object of the invention is to provide a sewer pipe cleaner which may be 20 easily attached to a rod and which will, when pushed through a sewer pipe, cut and work its way through obstructions with a minimum effort.

A further object of the invention is to 25 provide a sewer pipe cleaner which is of simple construction, is strong and durable and is well adapted for the purpose described.

With the above and other objects in view, 30 the invention consists of the improved sewer pipe cleaner and its parts and combinations as set forth in the claims, and all equivalents thereof.

In the accompanying drawing in which 35 the same reference characters indicate the same parts in all of the views: Figure 1 is a side view of the improved sewer pipe cleaner; one of the revoluble members being in section; and Fig. 2 is a sectional view 40 thereof taken on line 2—2 of Fig. 1.

Referring to the drawing the numeral 5 indicates a cleaning rod to which the improved sewer pipe cleaner 6 is connected by bolts 7. The sewer pipe cleaner comprises 45 the attaching stem 8 having a rear perforated flat rod connecting portion 9 and a stud shaft 10 extending from its forward rounded end 8' upon which a trunnion block 11 is swiveled. The trunnions 12 of the 50 block 11 project from diametrically opposite sides of the block and have cleaner members 13 journaled thereon which are approximately of hemi-spherical shape with their flat faces 14 toward each other. The mem-

bers 13 are spaced apart a distance slightly 55 greater than the thickness of the forward rounded end portion 8' of the stem to permit free rotation of the members. The members 13 are so positioned with relation to each other as to form a spherical end which is 60 adapted to be forced through the pipe to be cleaned and which will in advancing revolve on the stud shaft at the same time the spherical members are revolving on their trunnions. While the parts are thus revolving 65 the peripheral edges 15 of the members 13 will cut or work through any obstruction in the pipe and separate it into small parts which may be easily flushed out of the pipe.

From the foregoing description it will be 70 seen that it is only necessary to attach the cleaner to a rod and then force it back and forth through the obstructed pipe and the revoluble end will easily disintegrate the obstruction and clean the pipe. 75

What I claim as my invention is:

1. A sewer pipe cleaner, comprising a stem, a revoluble block swiveled on one end of the stem, and revoluble cleaner members journaled on the block. 80

2. A sewer pipe cleaner, comprising a stem, a revoluble block swiveled on one end of the stem, and revoluble cleaner members journaled on opposite sides of the revoluble block. 85

3. A sewer pipe cleaner, comprising a stem, a revoluble block swiveled on one end of the stem, and revoluble cleaner members journaled on opposite sides of the revoluble block, said cleaner members being of approximately hemispherical form and being journaled on the block to form approximately a spherical end to the stem. 90

4. A sewer pipe cleaner, comprising a stem, a revoluble block swiveled on one end 95 of the stem and provided with diametrically oppositely positioned trunnions, and hemispherical cleaner members journaled on the trunnions and having their flat faces extending toward each other, said cleaner members 100 being positioned to form approximately a spherical end to the stem.

In testimony whereof, I affix my signature, in presence of two witnesses.

FREDERICK E. GROSVOLD.
